UNITED STATES PATENT OFFICE

EMANUEL FROHMAN, OF GASTONIA, NORTH CAROLINA

ADJUSTABLE LUBRICATING MEANS

Application filed July 16, 1928. Serial No. 293,135.

My invention relates to a device for oiling the bearings of spinning frames, roving frames and the like, and has for an object thereof the provision of a wick for lubricating the bearing, said wick being mounted in a container and being adjustable with relation to the bearing and to the container.

An object of my invention is to provide a lubricating device for spinning frames, roving frames, and the like in which there is mounted a wick member adapted to engage the journal mounted in the bearing, said wick member having a coiled spring closely fitting therearound and projecting into a lubricant container in which is mounted an enlarged coiled spring, said enlarged coiled spring having a restricted portion adapted to engage the wick and the restricted portion of the enlarged coiled spring being adapted to follow the coiled spring mounted around the wick so that the two springs serve as a thread and nut for adjusting the wick with relation to the enlarged coiled spring.

Another object of my invention is to provide a lubricating device for spinning frames, roving frames and the like, having means for lubricating the bearings of the rollers mounted in the bearings by means of an adjustable wick mounted in a suitable container and communicating with the surface of said bearing.

Some of the objects of my invention having been stated, other objects will appear as the description proceeds, when taken in connection with the accompanying drawings, in which:—

Figure 1 is a side elevation of a roll stand showing my device applied thereto, the height of the roll stand being cut down and the size of my device being enlarged;

Figure 2 is a vertical, cross-sectional view taken through a portion of my device;

Figure 3 is a cross-sectional view taken through the stem portion of my device and looking downwardly, and showing the lubricating hole and vent hole exposed to view;

Figure 4 is a similar view showing the said holes closed by the washer.

Referring more specifically to the drawing, the numeral 10 indicates a conventional roll

stand having the bearing portion 11 and in this bearing portion I drill a hole as indicated at 12, in which I mount my device. My device consists of the tubular cup 13 having the cap 14 threadably secured on the upper end thereof, which cap has the neck portion 15, the upper end of said neck portion being threaded as at 16 and this neck portion has the hollow portion 17 in which I mount the wick 18, said wick extending downwardly into the portion 13. Around this wick 18 I secure the coiled spring 19 by having the closely wound portion 20 engaging the upper end thereof, and the lower end is pressed into the wick as at 21. Within the container 13 I mount the enlarged coiled spring 22, which has the restricted portion 23, which restricted portion is adapted to engage the wick so that this portion 23 falls between the various portions of the coiled spring 19, the portion 23 serving as a nut and the coiled spring 19 serving as threads on the wick so that by turning the wick with relation to the spring 22, the wick may be adjusted with relation to spring 22, and when the wick becomes worn away at its upper end, the portion 21 can be lifted out of the wick and the coiled spring 19 can be slid downwardly on the wick so that it is seen that the life of the wick is practically unlimited. The container 13 is adapted to be filled with a suitable lubricant and the portion 14 has the two holes 24 and 25 therein, the hole 24 being adapted to have the lubricant passed therethrough and the hole 25 allows the air to escape from within the container 13 as the air is displaced by the entrance of the lubricant. Around the neck portion 15 I loosely mount the washer 26, which has the broken away portion on one side thereof, as shown in Figures 3 and 4, which washer has the upwardly projecting portion 27 so that when the container is filled that a slight push on the portion 27 will cause the washer to assume the position shown in Figure 4 and close the said holes to prevent lint and dirt from entering the lubricant chamber.

In the drawings and specification I have set forth a preferred embodiment of my invention, and although specific terms are em-

ployed, they are used in a generic and descriptive sense only and not for purposes of limitation, the scope of the invention being set forth in the appended claims.

I claim:

5. 1. In a device for lubricating a bearing, the combination of a hole in said bearing, a lubricant container secured in said hole, a passage-way between the lubricant container and the 10 surface of said bearing, a wick mounted in the lubricant container and having a coiled spring secured therearound forming a thread on said wick, a second coiled spring mounted in the lubricant container and having a re- 15 stricted portion thereof adapted to engage the said wick between the coiled spring secured therearound to permit relative adjustment between the wick and the said last mentioned coiled spring.
20. 2. The combination with a journal comprising the usual bearing, a hole in said bearing, a wick guide mounted in said hole, a lubricant container detachably secured to said wick guide, a wick loosely mounted in said wick guide and projecting into the container, a coiled spring secured around the wick forming a thread, a coiled spring mounted in the lubricant container and being adapted to threadably engage the wick be- 25 tween the coiled spring secured therearound to force the same through the wick guide, the two coiled springs forming means for adjusting the said wick with relation to the coiled spring mounted in the container.
30. 3. In a bearing, a roller mounted for rotation in the bearing, a hole piercing the bearing, an oil cup mounted in the said hole, a wick mounted in the oil cup and being adapted to press against the roll mounted in the bearing, a coiled spring secured around the wick and forming a thread thereon, a sec- 35 ond coiled spring mounted in the oil cup and being adapted to threadably engage the wick and the first named coiled spring to permit relative adjustment of the wick and the sec- 40 ond coiled spring.
45. 4. In a lubricating device, a bearing, a shaft adapted to be rotatably mounted in the bearing, a lubricant container secured to the said bearing and having its interior portion communicating with the surface of the bearing, a wick mounted in the lubricant container and having its upper end in engagement with the bearing portion of said shaft, 50 a coiled spring tightly secured around the wick forming threads thereon, an enlarged coiled spring mounted around the wick and having a restricted portion adapted to snugly fit around the wick and to fall between the 55 portions of the first named coiled spring to permit relative adjustment between the wick and the said enlarged coiled spring, the enlarged coiled spring being adapted to press the wick into engagement with the bearing 60 surface.
65. 5. In a lubricating device, a bearing adapt- 70 ed to receive a shaft, a hole in the said bearing communicating with the surface thereof, a lubricant container mounted in said hole, a wick mounted in the said lubricant container and having its end adapted to engage the said shaft, a coiled spring snugly secured around the said wick to re-inforce the wick and forming a thread thereon, an enlarged coiled 75 spring mounted in the lubricant container and having a restricted portion adapted to threadably engage the wick to permit relative adjustment between the wick and the enlarged coiled spring, said enlarged coiled spring being adapted to press the wick into engagement with the bearing portion of said shaft.

In testimony whereof I affix my signature.
EMANUEL FROHMAN.
